UNITED STATES PATENT OFFICE.

GEORGE J. DOURTE, OF LONGMONT, COLORADO.

VALVELESS PUMP.

1,034,592.

Specification of Letters Patent.

Patented Aug. 6, 1912.

Application filed October 23, 1911. Serial No. 656,144.

To all whom it may concern:

Be it known that I, GEORGE J. DOURTE, a citizen of the United States, residing at Longmont, in the county of Boulder and 5 State of Colorado, have invented certain new and useful Improvements in Valveless Pumps, of which the following is a specification, reference being had to the accompanying drawings.

10 This invention relates to pumps and more particularly to a valveless pump of the double acting reciprocating type, the invention having for its primary object the provision of a very simple and compact arrangement 15 of parts whereby the necessity of employing the usual check valve is entirely eliminated.

A further object of the invention is to provide means whereby the interruption of the 20 operation of the pump by foreign material 25 which may be present in the fluid entering the pump cylinders is avoided.

Another object of the invention is to provide a compound cylinder pump having 30 25 transversely reciprocating and oppositely rotating pistons to automatically and alternately open and close the discharge and admission 35 ports of the respective cylinders.

A still further object of the invention resides in the provision of new and novel 40 30 means for forming an air-tight connection between the reciprocating pistons and the admission and discharge ports of the cylinders.

With the above and other objects in view, 45 35 the invention consists of the novel features of construction, combination and arrangement of parts hereinafter fully described and claimed, and illustrated in the accompanying drawings, in which—

40 Figure 1 is a side elevation of a double acting pump embodying my improvements; Fig. 2 is a top plan view; Fig. 3 is an end view; Fig. 4 is an enlarged vertical section taken on the line 4—4 of Fig. 1; Fig. 5 is a section taken on the line 5—5 of Fig. 4; Fig. 6 is a detail section taken on the line 6—6 of Fig. 4; Fig. 7 is a detail elevation of one of the saddle plates; Fig. 8 is a detail section taken on the line 8—8 of Fig. 3; Fig. 9 is a detail elevation of the sectional gear wheel; and Fig. 10 is a detail view 50 partly in section of the connecting yoke between the crank shaft and pistons.

55 In the accompanying drawings I have illustrated a pump of the double acting type wherein the cylinders 5 are vertically dis-

posed and are rigidly secured at their lower ends upon a suitable base 6. These cylinders have integrally formed upon their upper ends and extending in opposite lateral directions therefrom, the horizontal bracket plates 7 which include the inclined braces 8 also formed integral with said plates and the side walls of the cylinders. Upon the bracket plates 7 the standard 9 is arranged and is rigidly secured to said plates at its lower end by means of a plurality of bolts 10. The upper portion of this standard is bifurcated as shown at 11 to accommodate the gear 12 which is keyed or otherwise rigidly fixed upon the crank shaft 13 mounted in the bearings 14 on the upper end of the standard 9. The gear 12 would preferably, though not necessarily, be formed in two sections as shown in Fig. 9 of the drawings 70 and securely bolted together by means of the inner and outer bolts 15 and 16 respectively which extend through openings in flanges 17 formed upon the abutting edges of the gear sections. By providing these gear sections the same may be easily and quickly removed from the crank shaft without necessitating the removal of said shaft, so that the speed of operation of the pump may be changed without undue loss of time.

Upon the upper end of the standard 9 and on opposite sides of the bifurcation therein, the transversely disposed arms 18 are formed. These arms are provided with bearings 19 on their outer ends in which a 90 countershaft 20 is rotatably mounted. Upon this shaft between the bearings 19 a pinion 21 is keyed and said pinion meshes with the teeth of the gear 12 to transmit rotary movement to the crank shaft. A band 95 wheel or pulley 22 which may be connected to any suitable source of power is fixed upon one end of the countershaft 20.

In each of the cylinders 5 a vertically reciprocating piston 23 is arranged, and 100 these pistons are of substantially the same length as the cylinders and are each provided at an intermediate point with an internal head or wall 24. The annular wall of each piston above the head 24 has apertures 105 formed therein at diametrically opposite points to receive the ends of a wrist pin 25 and securing bolts 26 are longitudinally disposed in the piston walls and are conically formed at their lower ends for engagement 110 in the similarly shaped notches or seats 27 provided in the ends of the pin 25. The tip-

per ends of the securing bolts 26 have threaded engagement in the wall of the piston as shown at 28 whereby they may be readily adjusted to secure the wrist pin in 5 position or permit of its removal. Means are employed to connect the pistons to the crank shaft 13 whereby a combined reciprocatory and rotary movement is imparted to said pistons. This means is substantially 10 identical with that disclosed in my prior application for patent filed March 14th, 1911, Serial No. 614,392, and includes a connecting rod 29, which at its lower end is formed with a yoke 30 the arms of which 15 are longitudinally split as clearly shown in Fig. 6 and in the inner ends of the split arms, bushings 31 are arranged. Upon the wrist pin 25 a sleeve 32 is loosely arranged for rotary movement, and this sleeve is centrally provided at opposite points with the 20 trunnions 33 which are rotatably disposed in the bushings 31. The opposed portions of the split ends of the yoke arms are connected by means of the clamping bolts 34 25 whereby the bushings 31 are rigidly clamped in position therebetween. By this construction it will be noted that a universal movement is obtained between the connecting rod and the piston 23. The upper end 30 of the connecting rod is slightly reduced in diameter and provided with an annular flange 35. This reduced end of the connecting rod extends through a bushing 36 arranged between the arms of a yoke 37. This 35 yoke is loosely mounted upon the crank 13 on one end of the crank shaft 13, said shaft being rotatable in a bushing 38 which is rigidly held between the body portion and the top or cap 39 of the yoke by means of 40 the bolts 40. The reduced end portion of the connecting rod extends above the bushing 36 between the arms of the yoke and has arranged thereon the miter gear 41. This gear is rigidly fixed upon the end of 45 the connecting rod by means of a pin 42 which extends transversely through the rod and the tubular boss formed upon the gear. This gear meshes with a similar gear 43 which is splined or keyed upon the end of 50 the crank shaft. By means of this connection it will be readily seen that when the crank shaft is rotated the yoke 37 will swing thereon so that the gear which is arranged between the yoke arms will move upon the 55 toothed face of the complementary gear 43 on the crank shaft and rotary movement as well as reciprocatory movement will thus be imparted to the piston 23.

To each of the cylinders 5 upon one side 60 thereof the discharge head or pipe 44 is connected and to the walls of the cylinders at the opposite side thereof the suction head or pipe 45 is connected. The means for forming these connections between the pipes 44 and 45 and the cylinders constitutes a

very important and essential part of the present invention as it is imperative that these connections be made perfectly airtight and that wear between the periphery of the reciprocating pistons and the cylinder walls be compensated for. I secure the desired result by the provision of the saddle plates 46 which are arcuate in cross sectional form and are arranged within the cylinder, one pair of such plates being provided for 70 each cylinder and arranged at opposite points in the wall thereof. Annular flanges 47 are integrally formed with the saddle plates and project from their convex faces. This flange extends outwardly through the 75 openings 48 in the cylinder wall. The inner peripheral face of the flange 47 is provided with an annular shoulder 49 which is formed by reducing the thickness of the flange and into this reduced outer end of the flange 47 the circumscribing inner edge portion of a packing ring 50 extends. This packing ring may be of any desired material suitable for the purpose and is rigidly held in the end of the flange by means of a metal 80 ring 51 which is disposed upon the packing and is secured to the flange of the saddle plate by means of a plurality of screws 52 which extend through said metallic ring and the packing. The greater portion of the 85 packing ring 50 is disposed upon the exterior of the cylinder wall around the opening 48 thereof and is securely held thereagainst by means of the coupling ring 53 which is secured to the wall of the cylinder by the 90 bolts 54, suitable openings being provided in the packing ring for the reception of said bolts. The packing ring is also provided with additional openings 55 which are in line with the openings 56 formed through 95 the wall of the cylinder adjacent the edge of the opening 48 and at diametrically opposite points with relation thereto. In these 100 openings the coiled springs 57 are arranged and bear against the saddle plate 46 at their 105 inner ends, the outer ends of said springs engaging with the adjustable bolts 58. By adjusting these bolts the tension of the 110 springs may be regulated in accordance with the degree of friction which is necessary 115 between the inner concave face of the saddle plate and the periphery of the piston in order to form an air-tight connection. It will be observed that the end of the flange 47 on the saddle plate is slightly 120 spaced from the packing ring as indicated at 59 so as to permit of the flexing of said ring at this point as the saddle plate is forced inwardly by the springs 57, the flange 47 of said saddle plate moving freely 125 against the wall of the opening 48. In the wall of the hollow piston 23 below the intermediate head plate 24 thereof, an arcuate opening 60 is provided and this opening is adapted to register with the opening in 130

the saddle plate during the rotary movement of the piston. The lower portions of the walls of the cylinders wherein the saddle plates are disposed are reduced in thickness, and these enlarged lower ends of the cylinders provide vacuum chambers 61 by reason of the air-tight connections which are provided between the same and the suction and discharge heads. The pistons 23 fit closely against the walls of the narrower portions of the cylinders and the inner concave faces of the saddle plates 46. The upper ends of the cylinders are also of increased internal diameter and have arranged therein the adjustable collars 62 which are provided with the flanges 63 having openings therein for the reception of the bolts 64. These bolts are threaded into the upper ends of the cylinder walls and nuts 65 have threaded engagement on the upper ends of the bolts and engage with the flanges of said collars to secure the same in their adjusted positions. Between the lower ends of the packing collars 62 and an annular shoulder 62' on the inner wall of the piston cylinder, a packing ring 67 of any suitable material is arranged, and by adjusting the collar 62, said ring may be at all times disposed in close frictional engagement upon the periphery of the piston to prevent any leakage of the fluid upon the down stroke thereof.

The operation of my improved pump is as follows: When power is applied to the countershaft 20, rotary movement is transmitted to the crank shaft 13 and the pistons 23 are reciprocated in reverse directions in their respective cylinders. At the same time rotary movement is imparted to the pistons and in relative opposite directions in the manner previously described. Assuming that the pistons are in the positions shown in Fig. 1, upon the down stroke of the raised piston, the fluid will be discharged from the chamber 61 of the cylinder, the opening 60 in the wall of the piston immediately beginning to align with the opening of the saddle plate 46 at the start of this downward movement. The opening in the wall of the other piston is progressively moved into full register with the admission port of its cylinder and the fluid is being admitted to the chamber 61 of said cylinder. The pistons 23 moving in opposite directions in the cylinders, have their openings 60 disposed in complete alignment with the openings of the saddle plates of the inlet and discharge ports of the respective cylinders, when said pistons have completed one-half of their stroke and upon the completion of the piston stroke, the openings 60 thereof are entirely out of communication with the openings in the saddle plates. Upon the reverse movements of the pistons, they are simultaneously rotated in opposite directions and suction is created upon the up-

stroke of one piston to draw the fluid into the cylinder, the opening in the wall of said piston gradually moving past the opening in the saddle plate 46 both in a longitudinal and circumferential direction. Communication between the interior of the other piston and the discharge port is also gradually cut off until when the piston is at the lowest point of its stroke the positions of the openings in the respective pistons is reversed. Thus it will be seen that upon each stroke of the piston it also makes one-half of a revolution. The rotation of the pistons is continuous and the dimensions of the inlet and discharge openings to the piston cylinders is properly proportioned in accordance with the stroke of the pistons so that the admission and discharge of the fluid will be continuous. By providing the rotary as well as reciprocating pistons, a very powerful suction is created as the openings in the walls of the pistons pass the openings in the saddle plates.

Each of the cylinders is also provided with an opening in its wall at its lower end to which a drain pipe 66 is connected. These pipes preferably extend from opposite sides of the cylinders with respect to each other and drain the cylinders below the admission and exhaust ports.

In cases where it is desirable to pump fluids from one point to another and back again to the original depository, such return of the fluid may be readily accomplished by simply reversing the application of power to the shaft 20 and interchanging the inlet and discharge pipe nozzles so that what was formerly the discharge ports of the cylinders becomes the inlet ports and vice versa.

It will be understood that while I have specified the pistons as turning or rotating in opposite directions within their respective cylinders, this opposite rotation of the pistons is not essential to the utility of the apparatus but is the result of applicant's specific gearing for transmitting power to the pistons from the power shaft. The pistons may both rotate in the same direction if it is desirable to employ other power transmission means than that hereinbefore described.

From the foregoing it is thought that the construction and manner of operation of my improved pump will be fully understood. By the provision of the yieldingly held saddle plates, an absolutely air tight connection between the piston cylinders and the suction and discharge pipes is effected, the wear upon said plates being taken up by means of the springs 57 which at all times hold the concave faces of said plates in close engagement with the pistons. As the tension of these springs may be readily regulated, the proper amount of friction between the plates and the peripheries of the pistons can

be obtained. It will also be noted that my particular mounting of the various operating parts provides a very compact arrangement so that the pump may be readily installed and operated in places of restricted dimensions. The action of the pump is also very positive and owing to the comparatively few elements employed in the construction, it will be obvious that the device 10 may also be manufactured at small cost.

While I have shown and described the preferred construction and arrangement of the various parts, it will be understood that the invention is susceptible of considerable 15 modification without departing from the essential feature or sacrificing any of the advantages thereof.

Having thus described the invention what is claimed is:—

- 20 1. In a pump, a pair of cylinders each having an inlet and discharge pipe connected thereto, hollow pistons to reciprocate in said cylinders each provided with a head and having an arcuate opening in its annular wall, an operating shaft having a crank on each end, connections between said cranks and the pistons to reciprocate the pistons in reverse directions with respect to each other, co-acting means carried by the 25 pistons and said cranks to continuously rotate the pistons in their reciprocatory movement and alternately register the openings in the piston walls with the inlet and discharge pipes of the respective cylinders.
- 30 2. In a pump, a pair of cylinders each having an inlet and discharge pipe connected thereto, hollow pistons to reciprocate in said cylinders each provided with an internal intermediate head and an arcuate opening in its annular wall at one side of the head, and means for reciprocating said pistons in reverse directions with respect to each other and continuously rotating the pistons in opposite directions with respect to 35 each other whereby the openings in the piston walls are progressively and alternately brought into full registration with the inlet and discharge ports of the respective cylinders.
- 40 3. In a pump, the combination with a cylinder and a piston to reciprocate therein, said cylinder being provided with inlet and discharge ports, ports connected to the respective ports of the cylinder, and means 45 for effecting an air-tight connection between said pipes and the ports, said means including arcuate saddle plates yieldingly movable in the cylinder ports for frictional engagement with the periphery of the piston, flexible packing rings secured to said saddle plates and extending upon the outer wall of the cylinder, and means to secure the packing rings to the cylinder wall.
- 45 4. In a pump, the combination with a cylinder and a piston to reciprocate therein,

said cylinder being provided with inlet and discharge ports and a piston having an opening to register with said ports, inlet and discharge pipes connected to the respective ports of the cylinder, and means for effecting an air-tight connection between said pipes and the cylinder ports including spring held saddle plates frictionally engaging the periphery of the piston and provided with openings to register with the 75 opening in the piston.

5. In a pump, the combination with a cylinder and a hollow piston to reciprocate therein, said cylinder having inlet and discharge ports, said piston being provided with an opening in its annular wall, of inlet and discharge pipes, and means for effecting an air-tight connection between said pipes and the cylinder ports, said means comprising arcuate saddle plates frictionally engaging the periphery of the piston and provided with annular flanges movably disposed through the ports in the cylinder wall, and tensionally adjustable springs arranged in the cylinder wall and yieldingly holding the saddle plates in engagement with the piston.

6. The combination with a cylinder and a piston to reciprocate therein, said cylinder having inlet and discharge ports, of inlet and discharge pipes and means for effecting an air-tight connection between the same and the cylinder ports, said means comprising saddle plates of arcuate cross sectional form disposed within the cylinder and in concentric relation to the wall thereof, said plates having laterally extending annular flanges integrally formed therewith and movable in the cylinder ports, packing rings fixed to said flanges and extending upon the exterior of the cylinder and over the edges of said ports, coupling rings for the inlet and discharge pipes rigidly fixed to the wall of the cylinder and upon said packing rings, and means arranged in the cylinder wall and engaging said saddle plates to force the concave faces of the plates into close frictional engagement with the periphery of the piston.

7. The combination with a cylinder and a piston to reciprocate therein, said piston having inlet and discharge ports, of inlet and discharge pipes and means for effecting an air-tight connection between each of the pipes and the respective ports of the cylinder, said means including a saddle plate arranged within the cylinder and having an annular flange movable in the port thereof, a pipe coupling ring rigidly fixed to the cylinder wall, said wall being provided with openings therein upon opposite sides of the port, springs arranged in said openings bearing against the saddle plate to yieldingly hold the same in close frictional engagement with the periphery of the cylinder.

der, and means arranged in the coupling ring to adjust the tension of said springs.

8. The combination with a cylinder and a piston to reciprocate therein, the bore of said cylinder at its lower end being of increased diameter whereby an annular space is provided between the cylinder wall and the periphery of the piston, said cylinder having inlet and discharge ports, of inlet and discharge pipes and means for effecting an air-tight connection between the same and the cylinder ports, said means including saddle plates of arcuate cross sectional form disposed in the enlarged lower end of the cylinder and in concentric relation to the wall thereof, packing rings secured to said plates, means rigidly securing the outer edge portions of said rings to the outer face of the cylinder wall, and means arranged in the cylinder wall and engaging the saddle plates to yieldingly hold the same against movement and in frictional engagement with the periphery of the piston.

9. The combination with a cylinder and a piston to reciprocate therein, the lower end

of said cylinder being of increased internal diameter to provide a space between the wall thereof and the periphery of the piston, said cylinder having inlet and discharge ports, of inlet and discharge pipes and means for effecting an air-tight connection between the same and the cylinder ports including saddle plates movable in the ports of the cylinder and having concave faces to frictionally engage the periphery of the piston, packing rings fixed at their inner edges to said saddle plates, means securing the outer edge portions of the rings to the outer face of the cylinder wall, said rings flexing at their intermediate portions in the movement of the saddle plates, and springs mounted in the cylinder wall and engaging said saddle plates to yieldingly hold the same in engagement with the piston.

In testimony whereof I hereunto affix my signature in the presence of two witnesses.
